UNITED STATES PATENT OFFICE

2,445,608

CONNECTING PLUG

Wilbur O. Detweiler, Toronto, Ontario, Canada

Application December 7, 1946, Serial No. 714,855

1 Claim. (Cl. 173—332)

1

This invention relates to connecting plugs for electrical appliances. The object of the invention is to devise a plug which may be readily removed from the terminal to which it is connected. A further object of the invention is to devise a plug which can be removed without touching the appliance to which it is connected.

Plugs of this kind have been devised in the past, but they have all been open to objection on one ground or the other. In general they have been expensive to manufacture and awkward to use. According to the present invention, a connecting plug has been devised which can be made with but little departure from the most commonly used construction for such plugs and at very little extra expense. It can be removed without touching the appliance to which it is connected, which is an important feature when the plug is used for toasters, heaters, or other appliances which become hot when in use, avoiding burning of the fingers. In its preferred form the plug is made of two pieces each of which by the use of removable mould fillers or stoppers can be made in the same mould.

The objects of the invention are attained by the various features of construction hereafter described of which two important features are the provision of a slot or slots in a plunger, which is used for removing the plug from its terminal, combined with means on the plug itself which project into the slot or slots to limit the movement of the plunger and prevent it from being withdrawn from the plug. A further feature of the invention is provision of the inlet for the wiring at one side of the plug in the plane of the contacts so that when in use this connection does not interfere with the operation of the plug removing means. Other features lie in the formation of the guideway from two parts of a two-piece plug and the utilization of the connecting means for the two parts of the plug as the projection which passes through the slot or slots of the plunger. Other features of the invention will hereinafter appear from the following detailed description of the device, which is illustrated, by way of example in the accompanying drawings in which:

Figure 1 is an end view of the connecting plug;
Figure 2 is a side elevation;

Figure 3 is a side view of one of the pieces, showing the plug in its relation to a two-pronged terminal from which it has just been removed and showing in dotted lines the position of the plunger when the plug is in engagement with the terminal;

2

Figure 4 is an end view;

Figure 5 is a perspective view of the plunger; and

Figure 6 is a cross section on the line 6—6 in Figure 2.

In the various figures the corresponding parts are referred to by corresponding numerals.

The plug is formed of two pieces 10 and 11 of electrical insulating material, which are substantially identical. Each piece is provided with a longitudinal rectangular groove 10^a and 11^a respectively which co-operate to form a guideway extending from one end to the other of the plug substantially centrally thereof and opening at each end. The guideway is wholly enclosed, with the exception of a portion of the upper end as hereinafter described.

On either side of the central groove each piece 10 and 11 is provided with a groove 10^b and 11^b, respectively, which co-operate when the parts are secured together to provide recesses for conventional contact members 12 and 13, which comprise two slightly concavo-convex conductive parts held together at one end by screws or bolts in the usual manner.

The upper ends of the grooves 10^b and 11^b provide space for connecting wires 14 and 15 and these grooves extend across the plug at the upper end forming passageways which intersect the grooves 10^a and 11^a and provide passageways communicating between the recesses on either side of the guideway to carry one of the wires from one recess to the other for connection with one of the contacts.

A plunger 16 is slidable in the guideway formed by the grooves 10^a and 11^a and is provided with a head or knob 16^a. It extends longitudinally through the plug and beyond the ends thereof so that by grasping the plug and pressing on the head or knob 16^a the plunger may be forced inwardly into engagement with a terminal 17 to withdraw the plug from terminal prongs 17^a and 17^b which are adapted to enter and contact with the contacts 12 and 13. In practice two fingers will be placed around the enlarged outer or upper end of the plug and the thumb pressed on the knob 16^a to effect the removal of the plug from the terminal prongs.

Longitudinal slots 16^b and 16^c are provided in plunger 16 and connecting bolts 18 and 19 provided with suitable nuts on their ends and located substantially on the longitudinal centre line of the plug extend through the two parts of the plug and through the slots 16^b and 16^c to serve the double purpose of holding the two

pieces of the plug together and at the same time acting as stops to limit the movement of the plunger so that it can be withdrawn only to the point where its lower or inner end is substantially flush with the lower or inner end of the plug.

Grooves 10^c and 11^c are formed in each side of each piece of the plug adjacent the upper or outer end thereof at one side, which co-operate to provide between them an aperture to admit the electrical wires 14 and 15. It will be observed that the line of connection between the two pieces of the plug is substantially in the transverse plane of the contact members 12 and 13 and that the aperture for admission of the wires 14 and 15 is on the same plane. A suitable coiled wire sleeve 21 of ordinary construction may be provided in the usual manner for protecting the wires at their point of entry into the plug and to retain them in an outwardly extending position so that they will not interfere with the operation of plunger 16.

A suitable piece of fibre board or other insulating material 20 is mounted on shoulders in the plug between the plunger 16 and the passageway which intersects the guideway through which the wire 14 passes for connection with contact 12. In practice each piece of the plug will be of identical construction although oppositely disposed so that there is a passageway both above and below the plunger 16 for passage of a wire, but only one such passageway is required since only one of the two wires will pass through the same. By the use of suitable stoppers, filters, or plugs for closing grooves or recesses not required each piece may be made in the same mould. For instance the mould may be made with a groove on each side for forming the aperture to admit the electric wires. For one piece of the plug this groove can be filled by a stopper on the left side and for the mating piece it can be closed on the right side.

It is thought that the construction and use of the invention will be apparent from the above description of the various parts and their purpose. It is to be understood that the form of my invention herewith shown and described, is to be taken

as a preferred example of the same, and that various changes in the shape, size and arrangement of parts may be resorted to, without departing from the spirit of my invention, or the scope of the subjoined claim.

5 What I claim as my invention is:

A two-piece plug of electrical insulating material, each piece of the plug being formed with a longitudinal substantially central groove extending from one end to the other, said grooves forming between them a longitudinal guideway, a plunger slidably mounted in the guideway and adapted to extend beyond the ends of the plug, whereby by grasping the plug and pressing the plunger the plug may be removed from the terminal to which it is attached, each piece of the plug having formed therein a recess on either side of the central groove, said recesses forming between them spaces, electrical contacts mounted in said spaces, and each piece having grooves extending from the recesses to the exterior of the plug adjacent one end thereof and to one side of the plug in the transverse plane of the contacts to provide between them an aperture 10 to admit electrical wires, the plunger having at least one longitudinal slot through it, and the plug being provided with at least one connecting member extending through both pieces of the plug substantially on the longitudinal centre line 20 thereof and through the slot to connect the pieces and to limit the movement of the plunger relative to the plug.

WILBUR O. DETWEILER.
